UNITED STATES PATENT OFFICE.

PHILIP K. MCGALL, OF EAST ORANGE, NEW JERSEY, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed December 31, 1920. Serial No. 434,183.

To all whom it may concern:

Be it known that I, PHILIP K. MCGALL, a citizen of the United States, residing at East Orange, in the county of Essex, State of New Jersey, have invented certain new and useful Improvements in Electromagnetic Devices, of which the following is a full, clear, concise, and exact description.

This invention relates in general to electromagnetic devices and more particularly to an electrical relay of the slow-acting type.

In many circuits, such for example, as automatic telephone circuits, it is necessary to maintain a certain sequence of operation of the apparatus involved in the circuit and this is accomplished very often by the use of slow-acting relays. Heretofore, relays have been made slow-acting largely by the use of copper sleeves, which serve as short-circuited windings of very low resistance. By this means relays are obtained, the speed of operation of which is relatively slow for normal operating currents, but is greatly increased when operating with currents of higher value.

It is the object of the present invention to provide an electromagnetic device in which the time of operation is relatively slow. A further object is to provide such a relay in which the time of operation is independent of the operating current. A still further object is to provide a relay which is slow operating but quick releasing.

To accomplish these objects and in accordance with a feature of the invention, there is provided an electromagnetic device in which the time of operation is delayed by an escapement to take place a considerable period of time after the armature itself has reached its operated position.

In accordance with another feature of the invention, the operation of the armature allows a spring member to operate an escapement independent of the speed of operation of the armature itself. Another feature of the invention resides in providing a relay with an escapement which functions to slow down the time of operation, but which does not affect the time of release.

These and other features of the invention will be more fully understood by reference to the accompanying drawing in which Fig. 1 is a plan view of an electrical relay embodying the features of the invention; Fig. 2 is an elevation and Fig. 3 an end view of

the relay disclosed in Fig. 1; Figs. 4, 5 and 6 are plan, elevation and end views respectively of a modified construction in which the time of release is not retarded; Fig. 7 is a partial view of a one-way clutch as employed in the structure of Fig. 5; and Fig. 8 is a similar view of this clutch in the driving position.

Referring now to the drawing, there is disclosed in Figs. 1 to 3 a relay of the well-known flat type comprising an operating winding 5 having a core member 6 extending therethrough and provided with a substantially U-shaped armature 7. The legs of this armature are secured by means of flexible hinged members 8, 8, to the rearwardly-extending clamping plate 9 of core 6. Contact springs 10 and 11 are secured to the clamping plate 9 by means of screws 12, 12 and plate 13, and are insulated from each other by means of strips 14, 14 of micarta or similar insulating material. A threaded stud 15 is securely fastened to the end of core 6 and is provided with a shoulder nut 16, which is adapted to engage the armature 7 and limit its backward motion. Securely riveted or otherwise fastened to the legs of armature 7 near the hinged portion, are the free ends of a substantially U-shaped tension member 18. This member is provided with a right-angled projecting yoke 19 in which is secured a screw stud 20, which, in turn, is adapted to engage a perforation in an escapement lever 21. This escapement lever rotates about a pivot pin 22, which is secured between the side plates 23, 23 of a frame member fastened to the core 6. Also mounted upon one of the plates 23 is a clock pivot 24 upon which a weight member 25 is adapted to oscillate. Pins 26, 26, which are provided on the weight member, are adapted to engage the free end of lever 21 which is provided with saw-teeth 27, 27. A stud 28 is provided as shown, in either leg of armature 7, and by means of adjusting nuts 29, 29 it is possible to adjust the tension of member 18. Insulating studs 30, of hard rubber or similar material, are secured to the member 18 in alignment with contact springs 10, and in their movement contact springs 10 to engage contact springs 11. The side plates 23, 23 are provided with right-angled projections 31, 31, which serve as guides for a casing 32, which is held in place by means

of a spring 33 having a projecting portion 34, adapted to engage a similar portion in the casing.

The operation of the device is as follows: 5 upon sufficient current flowing through the operating winding 5, the armature 7 is attracted to core 6, overcoming the tension of the hinged members 8, 8. As a result of the movement of the armature the tension member 18 is permitted to exert pressure upon the lever 21 by means of the yoke 19 and stud 20. The lever 21 rotates about the pivot 22, but its rotation is delayed by means of the pins 26, 26, which alternately engage the 15 saw-teeth 27, thus causing the weight 25 to function as an escapement and oscillate back and forth. The movement of the member 18 is thus delayed, causing an appreciable interval of time before the contact springs 20 10, 10 have moved a sufficient distance to engage contact springs 11, 11. Upon the de-energization of the winding 5, the armature returns to its normal position against the nut 16 and in so doing, overcome the tension of 25 member 18, forcing it back slowly, due to the operation of the escapement.

It will be noted that in the structure disclosed, the time of operation is in no way dependent upon the speed of operation of 30 the armature itself, since the force exerted by member 18 is independent of the speed of operation of the armature. It is thus possible to provide slow-acting relays having a constant speed of operation irrespec- 35 tive of the operating current supplied.

Referring now to Figs. 4, 5 and 6, there is disclosed a modified construction in which the retarding means does not affect the time of release. A flat type relay of the same 40 general construction as shown in Fig. 1 is provided with an operating coil 40, an armature 41, and a core 42. The armature is pivoted to a clamping plate 43 by means of flexible hinged members 44, 44. The end 45 of core 42 is provided with a threaded stud 45 equipped with a shoulder adjusting nut 46, which limits the travel of armature 41 in one direction. Rigidly secured to the core 42 is a mounting frame 47 made of non- 50 magnetic material, such as brass, and having a substantially U-shaped cross section. Piv- 55 otally mounted within the frame 47 by means of pin 48, is a lever 49 having an end rack member 50, provided with teeth adapt- 60 ed to engage with pinion 51 which may rotate freely upon shaft 52. A disc member 53 is rigidly secured to the pinion 51 and co- 65 operates with an escapement wheel 54 and a dog 55 to provide a one-way clutch. The lower portion of the dog 55 extends through a slot 56 in escapement wheel 54 and is bifurcated and formed as shown to hold it in the desired position. The upper portion of dog 55 is provided with a recessed portion 57 through which the disc 53 may rotate

freely in a clockwise direction, as shown in Fig. 7. When the disc 53 is driven in a counterclockwise direction the dog 55 assumes the position shown in Fig. 8 and serves to drive the escapement wheel 54. 70 An escapement anchor 58 is arranged in operative relation to wheel 54 and is pivotally mounted to the frame 47 by means of the pin 59. The escapement anchor 58 carries the arm 60 provided at its free end, 75 with a slot portion adapted to engage the pin 61 mounted in a weight member 62, which is pivotally mounted to the frame by means of a pivot screw 63.

The armature 41 is provided with insulating studs 65, 65, which engage the free ends of tension springs 66, 66. Contact springs 67, 67 are provided with U-shaped sections 68, 68 which serve to limit the separation between the springs 66 and springs 67. The 80 springs 67 are also provided with right-angled projecting members 69, 69 upon which is pivotally mounted a U-shaped bracket 70 of insulating material. This bracket carries a pin 71 which engages a perforation in extension 72 of lever 49. Contact springs 73, 73 are provided to be engaged by contact springs 67, 67 upon sufficient movement of the latter. The contact springs 67 and 73 and the winding terminal springs 76 are 85 secured to the clamping plate 43 by means of screws 74, and are insulated from the plate and from each other by means of insulating strips 75, 75 of hard rubber or similar material. 100

Upon energization of the winding 40, the armature is drawn to the core 42 against the tension of springs 66, thus allowing the springs 67 to move in the direction of spring 73. This movement, however, is slow because of the escapement means provided. The movement of springs 67 causes the rotation of lever 49 through the medium of bracket 70, pin 71 and extension 72. 105

Referring to Fig. 4, the lever 49 tends to rotate about the pin 48 in a clockwise direction, and the rack portion 50 cooperates with the pinion 51, thus driving the disc 53 in a counter-clockwise direction as shown in Fig. 8. The dog 55 grips the disc 53 and causes the rotation of escapement wheel 54. As this wheel tends to rotate, the pallets of escapement anchor 58 ultimately engage the teeth of the escapement wheel and cause the oscillation of weight 62. The period of oscillation of the weight is purposely made low so that a considerable interval of time exists between the time when the armature 41 is attracted to the core 42 and the time when contact springs 67, 67 have moved an amount sufficient to cause them to engage contact springs 69, 69. Upon the release of armature 42, the movement is in a direction to cause the disc 53 to rotate in a clockwise direction, in which case the dog 110

115

120

125

130

55 assumes the position shown in Fig. 7 and allows the disc to rotate freely without driving the escapement wheel 54. The contact springs 67 are thus allowed to move quickly from springs 73, 73 and cause a quick opening of the contacts.

What is claimed is:

1. An electromagnetic device comprising an operating winding, an armature, switch springs, a member for actuating said springs and operated by the movement of the armature in one direction, means for retarding said member to cause it to actuate the springs a predetermined interval after the armature has completed its movement, and means for rendering said retarding means ineffective to delay the action of said member on the movement of the armature in the opposite direction.
2. An electromagnetic device comprising an operating winding, an armature, switch springs, a member for closing said springs actuated by the attraction of said armature, means for retarding said member to cause it to close said springs a predetermined interval after the armature has completed its movement, and means for rendering said retarding means ineffective to delay the opening of the springs on the retraction of said armature.
3. An electromagnetic device comprising an energizing winding, an armature therefor, a plurality of contact springs, an operating member, a connection between said member and said armature for causing the member to close said springs upon the at-

traction of said armature, means for retarding the movement of said operating member consisting of an escapement and an oscillating member in operative relation therewith, 40 said operating member being under the control of, but independent to the time of operation of said armature, and means for rendering said escapement ineffective on the return movement of said armature.

4. A circuit-controlling device comprising an energizing winding, an armature therefor, a plurality of contacts, an operating member controlling said contacts, a flexible spring member tensioned against 50 said armature and controlling the operation of said contacts, an escapement, a lever system connecting said operating member with the escapement and an oscillating member to govern the speed of operation of said escapement.

5. A circuit controlling device comprising an energizing winding, an armature therefor, a plurality of contacts, a flexible spring member tensioned against said armature controlling the operation of the contacts, an escapement retarding the movement of said spring member, a one-way clutch operable to prevent the operation of 60 said escapement in one direction and an oscillating member in operative relation with said escapement to govern the speed of operation of said escapement.

In witness whereof, I hereunto subscribe my name this 29th day of December, A. D., 70 1920.

PHILIP K. McGALL.
